(57) **CLAIM**

The ornamental design for a plumber mat as shown and described.

DESCRIPTION

FIG. 1 is a perspective view of the plumber mat of the present invention;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a second perspective view of the plumber mat of the present invention;

FIG. 9 is a right side elevation view of the plumber mat as shown in FIG. 8;

FIG. 10 is a left side elevation view of the plumber mat as shown in FIG. 8;

FIG. 11 is a top plan view of the plumber mat as shown in FIG. 8;

FIG. 12 is a bottom plan view of the plumber mat as shown in FIG. 8;

FIG. 13 is a front elevation view of the plumber mat as shown in FIG. 8; and,

FIG. 14 is a rear elevation view of the plumber mat as shown in FIG. 8.

The dash-dot-dot-dash broken lines in the drawings represent portions of the Plumber Mat which form no part of the claimed design. The dashed lines represent the boundary of the claimed design and form no part of the claimed design. Additional broken lines represent Symbolic breaks and are not part of the claimed design.

The plumber mat is shown with a symbolic break in its length and width. Any portion between the break lines, including the broken lines forming the break lines, form no part of the claimed design.
